US00D721215S

(12) **United States Design Patent**
Lee et al.

(10) **Patent No.:** US D721,215 S
(45) **Date of Patent:** ** Jan. 13, 2015

(54) **AUTOMATED TELLER MACHINE**

(71) Applicant: **Nautilus Hyosung Inc.**, Seoul (KR)

(72) Inventors: **Hee Yeon Lee**, Sungnam-si (KR); **Jae Min Cha**, Sungnam-si (KR)

(73) Assignee: **Nautilus Hyosung Inc.**, Seoul (KR)

(**) Term: **14 Years**

(21) Appl. No.: **29/483,620**

(22) Filed: **Feb. 28, 2014**

Related U.S. Application Data

(63) Continuation of application No. 29/470,001, filed on Oct. 16, 2013, now abandoned, which is a continuation of application No. 29/453,082, filed on Apr. 24, 2013, now abandoned, which is a continuation of application No. 29/387,325, filed on Mar. 11, 2011, now abandoned.

CLAIM

The ornamental design for an automated teller machine, as shown and described.

DESCRIPTION

FIG. 1 is a perspective view of an automated teller machine, showing our new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

Portions of the disclosure shown in broken lines form no part of the claimed design.
